UNITED STATES PATENT OFFICE

170,187

COMBINED WALLET AND HOLDER FOR
MANICURING AND SEWING ACCES-
SORIES

Norman Eichel, New York, N. Y.

Application March 5, 1953, Serial No. 23,921

Term of patent 7 years

(CL. D87—3)

To all whom it may concern:

Be it known that I, Norman Eichel, a citizen of the United States of America, residing in New York city, county of New York, and State of New York, have invented a new, original, and ornamental Design for a Combined Wallet and Holder for Manicuring and Sewing Accessories, of which the following is a specification, reference being had to the accompanying drawing, forming part thereof, wherein:

Figure 1 is a front elevational view of a combined wallet and holder for manicuring and sewing accessories showing my new design.

Figure 2 is a rear elevational view.

Figure 3 is an open perspective view thereof drawn to a smaller scale, and

Figure 4 is a side elevational view thereof.

I claim:

The ornamental design for a combined wallet and holder for manicuring and sewing accessories, substantially as shown.

NORMAN EICHEL.
